WELT TURNING AND FABRIC TAKE-UP
MECHANISM FOR STRAIGHT KNIT-
TING MACHINES

Peter J. Schoenster, Teaneck, and Max E. Ebert,
West New York, N. J., assignors to Alfred Hof-
mann & Co., West New York, N. J., a corpora-
tion of New Jersey

Application January 22, 1951, Serial No. 207,124

11 Claims. (Cl. 66—96)

1

This invention relates to welt turning and fabric take up mechanism for straight knitting machines of the "Cotton" type such as are ordinarily employed in the commercial production of full-fashioned hosiery and the like.

The present invention is concerned with welt closing mechanism of the general character disclosed in U. S. Patents Nos. 2,303,412, granted to F. M. Wachtler et al. on December 1, 1942, 2,363,000 granted to A. Hofmann et al. on November 1, 1944, 2,396,263 granted to said Hofmann et al. on March 12, 1946, and 2,401,531, granted to F. M. Wachtler et al. on June 4, 1946. The chief aim of our invention is to simplify and to generally improve such mechanism with a view toward securing more accurate and reliable performance therefrom and reducing the manual manipulations involved. Another aim of our invention is to provide a welt turning and fabric take-up mechanism having the foregoing attributes, which can be incorporated in standard makes of flat knitting machines without necessitating any structural changes in them and without interfering in any way with their normal mode of operation.

How the foregoing and other objects and attendant advantages are realized in practice will appear from the following detailed description of the attached drawings, wherein

Fig. 1 is a fragmentary broken out view in front elevation of a straight multi-section fashioned stocking knitting machine conveniently embodying our invention.

Fig. 2 is a cross section of the machine taken as indicated by the angled arrows II—II in Fig. 1.

Fig. 3 is a cross section taken as indicated by the angled arrows III—III in Fig. 1.

Fig. 4 is a fragmentary view in plan section taken as indicated by the angled arrows IV—IV in Fig. 3.

Fig. 5 is a cross section taken as indicated by the angled arrows V—V in Fig. 1.

Fig. 6 is a plan view looking as indicated by the angled arrows VI—VI in Fig. 5.

Fig. 7 is a cross section taken as indicated by the angled arrows VII—VII in Fig. 1.

Fig. 8 is a plan section taken as indicated by the angled arrows VIII—VIII in Fig. 7.

Fig. 9 is a cross section taken as indicated by the angled arrows IX—IX in Fig. 1.

Fig. 10 is a fragmentary perspective view of the parts shown in Fig. 9.

Fig. 11 is a cross section taken as indicated by the angled arrows XI—XI in Fig. 1.

2

Fig. 12 is a fragmentary view in top plan looking as indicated by the angled arrows XII—XII in Fig. 11.

Fig. 13 is a fragmentary broken out view in top plan looking as indicated by the angled arrows XIII—XIII in Fig. 1.

Fig. 14 is a fragmentary view in top plan generally like Fig. 13 but with portions shown in horizontal section.

10 Fig. 14a is a fragmentary view in section taken as indicated by the angled arrows XIVa—XIVa in Fig. 14.

Fig. 15 is a fragmentary detail view in cross section taken as indicated by the angled arrows XV—XV in Fig. 1.

Fig. 16 is a fragmentary view in top plan looking as indicated by the angled arrows XVI—XVI in Fig. 15.

20 Fig. 17 is a view like Fig. 15 with certain of the parts differently positioned.

Fig. 18 is a cross section taken as indicated by the angled arrows XVIII—XVIII in Fig. 1.

Fig. 19 is a view like Fig. 18 with certain of the parts differently positioned.

25 Figs. 20, 21, 22, 23 and 24 are perspective views of various parts embodied in the mechanisms of the machine.

Fig. 25 is a fragmentary view partly in elevation and partly in longitudinal section of one of the ware or take-up rollers of the machine.

30 Fig. 26 is a detail cross section taken as indicated by the angled arrows XXVI—XXVI in Fig. 25.

Fig. 27 is a detail view in cross section taken as indicated by the angled arrows XXVII—XXVII in Fig. 26.

Fig. 28 is a view in end elevation of the means relied upon for imparting rotary motion to the take-up rollers of the machine.

Fig. 29 is a fragmentary view in cross section showing the welt bar in hook up position relative to the knitting elements of the machine.

35 Figs. 30—36 are views like Fig. 29, showing successive relative positions assumed by the welt bar and the knitting instrumentalities during

40 Welt closing.

Fig. 37 is a fragmentary view corresponding to Fig. 3, showing a modification; and

45 Fig. 38 is a sectional view taken as indicated by the angled arrows XXXVIII—XXXVIII in Fig. 37.

50 With more specific reference first more particularly to Figs. 1—4 and 8—13 of the drawings, the numeral 1 designates the main longitudinally-extending cam shaft of the machine,

which, as usual, is rotatively supported in the spaced transverse frames 2 separating the several knitting sections. Also, as usual, the transverse frames are connected at the top by a front bed or rail 3 and a stationary rail 4 whereon the sinker heads 5 for the several knitting sections are fixedly mounted, and at the bottom by front and rear longitudinals 6 and 7. In each knitting section of the machine is a bar such as indicated at 8 in Fig. 2 carrying the needles 9 with which the endwise slidable sinkers and dividers 10 in the corresponding head 5 cooperate in the knitting, said needle bar being actuated in a well known manner from rotary cams (not shown) on the main cam shaft 1. Also cooperative with the needles 9 in the knitting as usual are knock-over bits such as shown at 11 in Figs. 29-36.

At the beginning of each knitting cycle, the starting course of fabric loops for each stocking blank in each section is formed, as ordinarily, over the hooks 15 of a welt bar 16 (Figs. 13, 14 and 20) which is thereafter gradually retracted until sufficient fabric for the welt is produced. It is to be noted that the protruding shank portions of the welt hooks 15 are longitudinally fluted or grooved at the bottom as at 15a and kinked at 15b, Fig. 29.

In accordance with our invention, each welt bar 16 is provided at its opposite ends with forwardly projecting shoes 17 constrained to longitudinal ways 18 of horizontally-arranged guides 19 which, at their rear ends, are secured to a rock shaft 20 rotatively supported in bearings on the transverse frames 2. As best seen in Figs. 14 and 20, the side recesses 21 of the shoes 17 of the welt bar 16 are overhung by leaf springs 22, and provided at their frontal ends with laterally-projecting round-ended trunnions 23 which normally bear against the sides of the ways in the guides 19. For a purpose later on explained, the inner or distal ends of the guides 19 are formed with rounded stop ends 25 (Fig. 21) which are adapted to serve as pivot bearings for the trunnions 23 on the welt bar 16, and set laterally into said guides with a force fit in coaxial relation to the stop bearing centers are studs 26 and 27 respectively. The stud 26, it will be observed from Fig. 14, terminates slightly short of the inner side face of the left hand guide 19 by a distance equal to half of the needle spacing for the provision of a spot indentation, and that the stud 27 is round ended and extends by a corresponding distance inward beyond the inner side face of the right hand guide 19 to provide a spot projection. During welt closing, the shaft 20 is turned counterclockwise slightly to lift the guides to the dash and dot position of Fig. 5 by means including a rotary cam 30 (Figs. 1, 5 and 6) on cam shaft 1. Fulcrumed on a fixed bracket 31 at the rear of the machine and extending forwardly over the cam shaft 1 is an arm 32 with a roller 33 thereon adapted to cooperate with cam 30. The arm 32 normally occupies the full line position in Fig. 5 with its distal end resting on a stop 35 adjustable in a bracket 36 on the frame rail 7, a tension spring 37 serving to yieldingly maintain said arm in engagement with said stop. Normally, also, the roller 33 is held out of the range of cam 30 but, at the proper times, it is shifted into the path of the latter by a forked lever 38 pivoted at 39 on arm 32, said lever having a tail 38a which, by means of a spring 40 is held in engagement with a stop lug 41 on an endwise shiftable control rod 42 extending lengthwise of the machine. By

means of a link 43, the arm 32 is connected to an arm 45 fast on the rock shaft 20 whereto the guides 19 are affixed.

For the purpose of advancing and retracting the welt bar 16 inward and outward on the guides 19 relative to the knitting instrumentalities as required in welt starting and turning, there is provided, on the cam shaft 1, see Figs. 1, 2, 3 and 4, a second rotary cam 50 with two treads 50a and 50b which are of different configurations. Overreaching the cam shaft 1 is an arm 51 which is fulcrumed on a bracket 52 upstanding from the frame rail 6, and which carries a roller 53 adapted to cooperate at different times with the treads 50a and 50b of cam 50. A spring 55 is relied upon to normally maintain the distal end of arm 51 in yielding engagement with a stop stud 56 adjustable in a bracket 57 on the frame rail 7. Pivoted at 58 on the arm 51 is a lever 59 by which the roller 53 is shiftable into the range of the cam treads 50a, 50b, the tail 59a of said lever being yieldingly held in engagement with a lug 60 on control rod 42. By means of a link 61, the arm 51 is connected to lever 62 affixed to another rock shaft 63. Also affixed to the shaft 63 in each knitting section of the machine are arms 65 which, in turn, are connected by means of links 66 to the corresponding welt bar 16 adjacent each end of the latter. As shown in Fig. 22, each link 66 is of composite construction; i. e. it has two telescopically interengaged main components 67 and 68. The component 67 is tubular, and threaded into one end thereof for purposes of adjustment is the shank of a pivot ear 69 for connection by a screw to the arm 65, said end being split as at 71 and surrounded by a clamp collar 72 to hold said ear against accidental displacement in adjusted position. The component 68 is movable axially relative the component 67 and is connected with a lug 73 at the inner end of shank of ear 69 by a helical tension spring 75 which acts to normally maintain a collar 76 on said component 68 in engagement with the opposite end of component 67. A stop screw 77 engaged in the component 67 serves, in cooperation with a collar 78 on the telescoped end of the component 68, to limit the extent to which the latter can be withdrawn and also as a means to keep the parts assembled. The reduced external prolongation 79 of component 68 of each link 66 terminates in an eye 80 which is received in a notch 81 (Figs. 14 and 20) in the rear edge of the welt bar 16 for attachment thereto by a pivot screw 82.

As in Patent 2,401,531, the machine is provided with a pair of arms 83 (see Figs. 11, 13 and 15-17) for each knitting section, said arms being affixed to a longitudinal shaft 84 rotative in stationary arms 85 fast upon a shaft 20 which is supported by brackets 87 on the front bed 3 of the machine. Normally, the arms 83 occupy the retracted position in which they are shown in Fig. 15 and have notched recesses 88 in their swinging ends overhung by spring tongues 88 to receive the opposite ends of a welt rod R for temporary retainment and support of the latter, said rod being manually applied after welt bar 16 has been "hooked" up at the beginning of the knitting cycle. The arms 83 are manually swung from the position in Fig. 15, through broken line position in Fig. 11 to the position in Fig. 17 to deposit the rod R upon the welt fabric F at sometime before welt bar 16 is advanced to close the welt. This is accomplished by means of a hand lever 89 (Figs. 1, 18, 19) affixed to shaft 84. During the inward swing of

arms 83, as just explained, a roller stud projection 90 on another fixed arm 91 on shaft 84 engages into the cam hook of a latch element 92 which is pivoted at 93 on bed 3 and is subject to the influence of a spring 94. The function of element 92 is to yieldingly impart additional movement to arms 83 at the completion of their inward swing and thereby depress and impose a slight tension upon the welt fabric F as shown in Fig. 17. Upon subsequent retraction of the arms 83, the elements 92 yield to displacement, as permitted by the spring 94 for release of the roller arm 91. Also secured to shaft 84 (see Figs. 18 and 19) are forked levers 95, each having one of its tines prolonged and curved as at 96 for camming action with a lateral projection 97 at the distal end of one of the arms 65 on shaft 63.

After the formation and closing of the welt, and during the completion of the stocking blanks, the webs are drawn off by ware roller 100 of which there is one provided for each blank. Except, as presently pointed out, the mechanism herein shown for actuating the ware rollers 100 is generally similar to that disclosed in Patent 2,396,263 since it comprises a longitudinally-extending shaft 101 which is rotative in fixed bearing brackets 102 on the transverse frames 2 and on which said rollers are mounted, see Fig. 7. In accordance with our invention, each roller 100 is constructed with a wooden body 103 (see Figs. 25, 26) to the opposite ends of which are secured, by means of screws 104, metallic heads 105 which are in turn secured, by means of set screws 106, to shaft 101. Freely mounted on shaft 101, are disks 107 having peripheral flanges 107a to partially overlap the heads 105, the collars shown at 108 serving to prevent axial displacement of said disks relative to the body of roller 100. The disks 107 are machined as at 109, for connection by means of screws 110, of the stepped ends 111 of bars 112 having lateral ways 113 for the guidance of flexible metallic tapes 115. As shown in Figs. 2 and 7, the guide bars 112 extend inward of the machine for support horizontally by the bed 3 whereto they are secured by clamp screws 116. The rear end portions of tapes 115 are bent laterally and retroverted as at 117, in Fig. 26 for anchorage in radial slits 118 in the peripheries of the disks 105. The tapes 115 are moreover apertured at intervals, as at 119, for positive engagement by tooth projections 120 on the roll heads 105; and are provided at lengthwise intervals with studs 121 that extend upward into retaining grooves 122 formed longitudinally of the bottoms of the guide-ways 113, see Figs. 26 and 27. The distal ends of the guide bars 112 are curved upwardly as at 123 (see Figs. 2, 7 and 23) to avoid interference with the movements of the needle bar 8; and the tapes 115 terminate in rearwardly-open spring hooks 124 for engaging diametrically-reduced ends of the welt rod R, as and for a purpose also later explained. Fast on the roller shaft 101 at one end of the machine is a drum 126 whereto is secured one end of a weight rope or cable 127 which tends to rotate said shaft 101 in the direction of the arrow W in Fig. 28. The drum 126 is provided as usual with a crank handle 128 and with slip ratchet means so that it can be turned in the direction of arrow U to wind up the weight cable 127 in preparation for taking up the fabrics after the welts are turned.

Incident to welt turning, the rollers 100 are reversely turned to slack the welt fabrics by the means about to be described by reference now to Figs. 1, 7 and 8. This means is arranged to

be actuated from another rotary cam 140 on cam shaft 1 through an arm 141 fulcrumed on a bracket 142 upstanding from the bottom frontal frame rail 6. The arm 141 carries a roller 143 which is shiftable into and out of the path of cam 140 by a fork lever 145 pivoted at 146 on said arm with its tail end maintained in engagement with another lug 147 on slide rod 42 by a spring 148. The downward movement of arm 141 is limited by a stop abutment 149 adjustably supported by the bracket 142. A link 150 connects arm 141 with a gear sector 151 which is free on another longitudinal shaft 152 of the machine and which meshes with a gear pinion 153 free on roller shaft 101. A spring-biased pawl 155 on the pinion 153 is adapted to cooperate with a ratchet wheel 156 fast on roller shaft 101 when the gear sector 151 is actuated as later on explained to reversely rotate said shaft during welt closing.

The rollers on the cam follower arms are shifted by means including transversely arranged rock shaft 160 (Figs. 1, 9 and 10) which has rotative support in still another upstanding bracket 161 on the rear bottom frame rail 6 of the machine. Pivoted at 162 to a collar 163 at the inner end of shaft 160 is an arm 164 which is subject to spring 165 to normally keep the roller 165 on said arm retracted from a rotary actuating cam 167 on the cam shaft 1. Cam 167 has a circumferential ridge 168 with a cut-out 169 for clearance of the roller 165, one edge of said cut-out being beveled as at 170 for camming action with said roller. Affixed to the outer end of rock shaft 160 is an upright lever 171 which has a longitudinal slot 172 for engagement by the laterally-projecting stud 173 of a collar 175 set upon the rod 42, whereby the latter is shifted rightward in Fig. 10 upon actuation of the roller arm 164 by cam 167. Roller arm 164 is adapted to be controlled from the usual timing chain (not illustrated) of the machine through a pull wire 177 connected to a drop lever 178 at one end of a short rock shaft 179 which is supported in bearings 180 along the boss of bracket 161. A horizontal lift lever 181 adjacent the inner end of shaft 179 underreaches a stud projection 182 at the back of roller arm 164. Accordingly, as wire 177 is pulled toward the left in Fig. 10, the roller arm 164 will be swung inward into cooperative relation with rotary cam 167. In order to insure that the welt rod holder arms 83 are raised sufficiently out of the way of the welt bars as the latter are advanced in welt turning, we have devised safety means for the description of which Figs. 1, 2, 11 and 12 will be now referred to. As shown, this means comprises an arm 185 fast on the usual narrowing shaft 186 of the machine which shaft is rotatively supported in bearings (not illustrated) in the lower part of the machine framework. Pivotedly connected to arm 185 is an upwardly-extending rod 187 which, adjacent its upper end, is guided for up and down movement in an apertured plate 188 secured to the front bed 3 of the machine, and of which the upper end is bent at right angles as at 189 to under-reach a finger 190 on shaft 84 of the welt rod holder arms 83. Thus, as rod 187 is lifted, arms 83 are moved upward to raise the welt rod R out of the way of the welt bar 16 when the latter is advanced incident to welt closing as presently explained. In the event that the narrowing mechanism of the machine should fail to function for any reason the roller arm 164 (Figs. 9 and 10) will be prevented from being moved to

ward rotary cam 167, through a finger 191 on shaft 186, which underreaches a stud 192 at the swinging end of a pendent arm 193 fixed upon the shaft 162 of said roller arm.

At the beginning of each knitting cycle of the machine, the welt bars 16 are simultaneously moved inwardly part way along the guides 19 from the idle or retracted full line position in Figs. 2, 3 and 13 to the position A in Fig. 14 to the position of Fig. 29 with their hooks 15 entered between the needles 9 at the level of the clearance between the sinkers 10 and knockovers 11, in readiness to receive and hook the first course of fabrics loops. This action is initiated automatically through pull upon cable 177 (Fig. 9) under the influence of the control chain of the machine, with the result that shaft 179 is actuated and the roller 165 on arm 164 thrust into the path of ridge 168 of rotary cam 16 on main cam shaft 1 as shown in broken lines in Fig. 9. During the ensuing rotation of cam 167, shaft 160 is turned clockwise in Fig. 10 through a short distance and shifter rod 42 thus moved rightward by arm 171 to a corresponding extent. By this shift of rod 42 lever 59 (Figs. 3 and 4) is moved to place the rollers 53 on arms 51 into the range of cam 50a on cam shaft 1. Accordingly, during the current rotation of cam shaft 1, arm 51 is lifted to the position H in Fig. 3 with consequent impartation of the inward thrust to the welt bars 16 as above stated through link 61, arms 62, 65 and links 66. In advancing the welt bars 16 in the hook up phase, links 66 are lifted to an angular position as shown in Fig. 19. To avoid interference with links 66 at this time, welt rod holder arms 83 are lifted through impartation of a clockwise shift to their supporting shaft 84 which is induced by camming action of studs 97 on arms 65 with the forked levers 95 on said shaft after the manner clearly shown in Fig. 19. At the completion of the current rotation of the cam shaft 1, the pull upon cable 177 is relaxed to allow spring 166 (Fig. 10) to retract the roller arm 164 from cam 167, whereupon the parts in Figs. 3 and 4 all resume their normal inactive positions.

The machine thereupon operates in the usual way to produce the welt fabrics. After this knitting has proceeded to about the extent shown in Fig. 17, tapes 115 are advanced in guides 112 to the position B in Fig. 23 by manually turning the ware rollers 100 clockwise in Fig. 7. With this accomplished, shaft 84 is turned by means of hand lever 89 to swing welt rod holder arms 83 inward from the retracted position of Fig. 15 to the position of Fig. 17, to deposit the welt rods R upon the fabrics F, as shown in the latter illustration. As the arms 83 are so swung, rollers 90 on arms 91 will cam into the hook bights of the elements 92, and due to the influence of the springs 94 upon said elements, rods R will press downward upon the fabrics F to tension the latter. With the welt rods R now in position, the rollers 100 are manually turned counterclockwise in Fig. 7 to draw back the tapes 115 until the clips 124 at the distal ends thereof engage the welt rods R as instanced in full lines in Fig. 23.

At the completion of welt fabrics of a predetermined length, the main cam shaft is shogged axially under control of the chain of the machine as in an ordinary fashioning step of the machine. At the same time, cable 177 is again pulled, as in the hook up stage previously described, to cause arm 164 (Figs. 9 and 10) to be actuated once more for displacement of its roller

165 into the range of cam 167. By this action, roller 53 on arm 51 will again be shifted as before, but due to the shog of cam shaft 1, will now be placed into the path of the cam 50b.

Also, by the above mentioned shog of cam shaft 1, cam 140 is brought into the plane of the roller 143 on follower arm 141 so that the roller released mechanism of Fig. 7 is actuated concurrently with the welt closing advance of the welt bars 16 and roller 33 (Figs. 5 and 6) on follower arm 32 concurrently shifted into position to be acted upon by rotary cam 30, as about to be explained. By action of cam 30 upon follower arm 32, shaft 20s is turned counter-clockwise slightly through the intermediary connections 43 and 45 with said arm, to raise the welt bar guides 19 to the angular broken line position of Fig. 5 as said bar 16 is thrust inwardly by the action of cam 50 (Fig. 3) upon follower arm 51. Due to the high rise of cam 50, the welt bars 16 are thrust inward to a much greater extent this time than they were during the hook up phase previously described. As the bars 16 are moved inward, they are arrested upon engagement of their trunnions 23 in the curved stop ends 25 of the guides 19, and, by the excess thrust, caused to be swung about the axes of said trunnions through the angular positions shown in broken lines in Fig. 3.

However, before reaching its extreme inward position, each welt bar is shifted laterally to the position C in Fig. 14 as its trunnion 23a cams with the stud 27 for alignment of its hooks 15, this time with the needles 9. By action of cam 140 (Fig. 7) upon the follower 141, the gear sector 151 is swung, by motion imparted thereto through the medium of link 150, approximately through a quadrant to the position indicated in broken lines. The pinion 153 is thereby rotated and its rotation communicated by coaction of the pawl 155 with the ratchet wheel 156, to the rollers 100 which are thus turned to the same extent. In this way, the fabrics F are relieved as the tapes 112 are advanced and the welt rods R with them concurrently during the inward welt folding and closing stroke of the welt bars 16. As the cam shaft 1 completes its current rotation and is shogged back to its original position axially, the cable 177 is released to permit the various parts in Figs. 3, 5 and 9 to resume their normal inactive positions with the welt bars now free and again fully retracted. As the sector 151 returns, pinion 153 turns with it, the pawl 155 slidingly over the teeth of ratchet wheel 156 without impartation of any rotation to the rollers 100.

Fig. 29 shows the relative positions assumed by a needle, a sinker and a welt bar hook during the hook up cycle. The needle 9 is descending to draw the loop from the nib of the reeding sinker 10 down onto the hook 15 of the welt bar 16 which is then retracted as hereinbefore explained.

Figs. 30-36 show various positions assumed by the welt bar during the welt closing phase. In Fig. 30, the sinker 10 is fully retracted and the hook 15 positioned with its knee point just slightly above the recess of the knock over 11. The hook remains in this position until the sinker 9 has advanced to hold the loop thereon below the sinker line. In Fig. 31, the sinker 10 has been advanced over the loop on the hook 15 and the needle pressed forward into the groove at the underside of the hook shank, said hook having assumed a position more nearly vertical. In Fig.

32, the needle 9 has risen slightly while in press with the hook 15 and has passed up through the loop on said hook 15. In Fig. 33, hook 15 has been raised out of press relation to the needle 9 and at the same time tilted rearward slightly while the needle has been raised in unison with it, the needle having passed partially through the loop. The needle then stops approximately in this position while the hook 15 rises to the position in which it is shown in Fig. 33. As soon as the hook has risen sufficiently for clearance of its groove from the needle, the hook will tend to push through rightward in Fig. 3, this action taking place when the hook reaches the thin portion of the needle. Fig. 34 shows the relative position of the parts just prior to disengagement of the hook from the now transferred loop. In Fig. 35, the hook has been lowered slightly approximately to the sinker line, and has receded somewhat further for release from the loop, while in Fig. 36, the hook has fully receded from the loop and is now entirely free of the fabric, whereupon the welt bar is withdrawn to idle position.

After the welts are closed, the fabrics are drawn off during the ensuing knitting by pull of the straps 115 upon the welt rods R, said straps being wound about the end portions of the rollers 100, the shaft 101 is turned by the drum 126 (Fig. 28) under the influence of the weight cord 127.

In instances where there is insufficient room available to permit installation in machine of stop brackets like the one indicated at 57 in Figs. 3 and 4, we resort to the modification construction illustrated in Figs. 37 and 38. Here the cam follower arm 51 is provided with a pendent clevised projection 195 for journalling of a roller 196 which is adapted to ride upon the periphery of an auxiliary wheel 197 clamped to the cam shaft 1 alongside the cam 50 and which thus serves as a stop for the arm, the tread of said wheel being concentric with the shaft axis. In the modification, the roller 53 which is axially shiftable by means of the fork 59, is freely rotative with interposition of a pin bearing 198 upon an eccentric portion 199a of a pin 199 secured by a set screw 200 in the arm 51 by this arrangement makes possible the adjustment of roller 53 relative to the cam 50 as will be readily understood. If necessary or desired, a similar construction may of course be used for the cam follower arm 32 of Figs. 5 and 6.

Having thus described our invention, we claim:

1. In welt turning mechanism for a straight knitting machine having a series of needles and a series of cooperating sinkers, said mechanism comprising a welt bar with hooks normally aligned with the needles and with slide shoes at opposite ends thereof; transversely arranged guide bars with supporting ledges for the slide shoes of the welt bar, and with stops at their inner ends to cooperate with trunnions at the forward ends of the shoes for pivoting of the bar during welt closing; means for advancing the welt bar forwardly part way along the guides to receive the starting course of the knitting in its hooks and for advancing the bar to the full extent for welt turning; and means automatically operative as the welt bar is advanced as last stated to shift it laterally slightly to position its hooks centrally of the intervals between the needles, the last mentioned means including a lateral spot projection at the stop end of one of the guides to cam with the trunnion on the corresponding shoe of the welt bar, and a lateral

spot depression at the stop end of the other guide to receive the trunnion on the other shoe of said bar.

2. Welt turning mechanism, according to claim 1, wherein the stop ends of the guides are rounded; and wherein leaf springs on the shoes of the welt bar overreach the trunnions and co-operate with the rounded ends of the guides to prevent displacement of the bar as it is turned about the trunnion axes incident to transfer of the starting course of fabric loops on its hooks back to the needles in welt turning.

3. In welt turning and draw-off mechanism for a straight knitting machine having a series of needles and a series of cooperating sinkers, said mechanism comprising a welt bar with hooks; transversely-arranged guide means on which the welt bar is slidably supported; means for advancing the welt bar on the guide means to receive the starting course of the knitting in its hooks and for yieldingly retracting it as the welt fabric is being formed; means for depositing a welt rod on the welt fabric forward of the welt bar after a portion of the welt fabric is knitted; means operative upon completion of a prescribed length of welt fabric for advancing the welt bar to transfer the starting course of the fabric back to the needles to close the welt; and separate means operative to thereafter draw off the fabric during continued knitting including a draw off roller with yielding means for turning it, metallic tapes connected to the periphery of the roller adjacent opposite ends thereof, said tapes having apertures at lengthwise intervals adjacent one of their side edges for engagement by peripheral teeth on the roller ends, hooks at the distal ends of the tapes for engaging the opposite ends of the welt rod, and transversely-arranged bars with lateral slots in which the opposite side edges of the tapes are guided.

4. In welt turning mechanism for a straight knitting machine having a cam shaft, a bar with needles, a cooperative series of slide sinkers, and a main cam shaft, said mechanism comprising a welt bar with hooks; transversely-arranged guide means on which the welt bar is slidably supported; means for advancing the welt bar on the guide means to receive the starting course of the knitting in its hooks and for yieldingly retracting it as the welt fabric is being formed; means for depositing a welt rod on the welt fabric forward of the welt bar after a portion of the welt fabric is knitted; means operative upon completion of a prescribed length of welt fabric for again advancing the welt bar to transfer the starting course of the fabric back to the needles to close the welt and for withdrawing said bar after the transfer has been effected; and means for automatically lifting the welt rod holder means clear of the path of the welt bar during the second advance of the latter.

5. Welt turning mechanism, according to claim 4, wherein the lifting means comprises an arm on the fulcrum axis of the welt rod holder means; and means actuated from the cam shaft of the machine to cooperate with said arm to effect the lifting.

6. In welt turning mechanism for a straight knitting machine having a cam shaft, and a series of needles and a series of cooperating sinkers, said mechanism comprising a welt bar with hooks; transversely arranged guide means on which the welt bar is slidably supported; means actuated from the cam shaft of the machine during a normal knitting phase for ad-

vancing the welt bar on the guide means to receive the starting course of the knitting in its hooks and for yieldingly retracting it as the welt fabric is being formed; means for depositing a welt rod upon the welt fabric forward of the welt bar after a portion of the welt fabric is knitted; means actuated from the cam shaft upon axial shifting of the latter as in a narrowing phase of the machine upon completion of a prescribed length of welt fabric to advance the welt bar a second time to close the welt and to retract it after transfer of the starting course back to the needles; and safety means to prevent actuation of the welt bar advancing means in the event of maloperation of the narrowing mechanism.

7. In welt turning and draw-off mechanism for a straight knitting machine having a cam shaft and a series of needles and a series of cooperating sinkers, said mechanism comprising a welt bar with hooks; transversely-arranged guide means on which the welt bar is slidily supported; means actuated from the cam shaft for advancing the welt bar on the guide means to receive the starting course of the knitting in its hooks and for yieldingly retracting it as the welt fabric is formed; means for depositing a welt rod on the welt fabric forward of the welt bar after a portion of the welt fabric is knitted; means actuated upon axial shifting of the cam shaft as in a narrowing phase of the machine to advance the welt bar to transfer the starting course of the fabric back to the needles to close the welt, the last mentioned means including an arm with a roller thereon and means for shifting the roller into the range of a rotary cam on the cam shaft; and safety means including a stop arm on a shaft associated with the narrowing mechanism for restraining said roller arm to prevent shifting of the roller thereon into the range of the aforesaid cam in the event of maloperation of the narrowing mechanism.

8. Welt turning mechanism according to claim 1, wherein the welt bar advancing means includes a rotary cam on the cam shaft, a wheel alongside the cam on the cam shaft having a tread concentric with the shaft axis, a roller on the arm normally riding on the tread of the wheel, a pin rotatively adjustable in the arm and having a projecting eccentric end portion, and a roller axially shiftable on said eccentric portion of the pin into the path of the aforesaid cam.

9. Welt turning mechanism according to claim 1, further comprising means for imparting a lift movement to the welt bar as it is advanced, said means including a rotary cam on the cam shaft, a wheel alongside the cam on the cam shaft having a tread concentric with the shaft axis, a roller on the arm normally riding on the tread of the wheel, a pin rotatively adjustable in the arm and having a projecting eccentric end portion, and a roller axially shiftable on said eccentric portion of the pin into the path of the aforesaid cam.

10. In welt turning mechanism for a straight knitting machine having a series of needles and

a series of cooperating sinkers, said mechanism comprising a welt bar with hooks; transversely-arranged guide means whereon the welt bar is slidily supported; means for advancing the welt bar on the guide means to receive the starting course of the knitting in its hooks and for yieldingly retracting it as the welt fabric is being formed; welt rod holder means swingable forwardly from a retracted position about a horizontal axis to deposit the welt rod upon the welt fabric forward of the welt bar; and means influential upon said holder means to maintain the welt bar yieldingly depressed until the desired length of welt fabric is knitted, including a spring-biased element fulcrumed about a fixed pivot axis, said element having a cam notch to cooperate with a stud projection on an arm secured to the pivot axis of said welt rod holder means as the latter is swung to deposit the rod.

11. In welt turning and draw-off mechanism for a straight knitting machine having a series of needles and a series of cooperating sinkers, said mechanism comprising a welt bar with hooks; transversely-arranged guide means on which the welt bar is slidily supported; means for advancing the welt bar on the guide means to receive the starting course of the knitting in its hooks and for yieldingly retracting it as the welt fabric is being formed; means for depositing a welt rod on the welt fabric forward of the welt bar after a portion of the welt fabric is knitted; means operative upon completion of a prescribed length of welt fabric for advancing the welt bar to transfer the starting course of the fabric back to the needles to close the welt; and separate means operative to thereafter draw off the fabric during continued knitting including a draw-off roller with yielding means for turning it, metallic tapes connected to the periphery of the roller adjacent opposite ends thereof, said tapes having apertures at lengthwise intervals adjacent one of their side edges for engagement by peripheral teeth on the roller ends, hooks at the distal ends of the tapes for engaging the opposite ends of the welt rod, transversely-arranged bars with lateral slots in which the opposite side edges of the tapes are guided, and longitudinally-spaced studs on the tapes engaged with lengthwise grooves offset from the slots in the guide bars for retention of the tapes in said slots.
